UNITED STATES PATENT OFFICE.

BARTON S. SNOW, OF BATAVIA, ILLINOIS, ASSIGNOR TO T. W. SNOW CONSTRUCTION COMPANY, OF CHICAGO, ILLINOIS, A CORPORATION OF ILLINOIS.

CRANE.

Application filed July 3, 1922. Serial No. 572,587.

To all whom it may concern:

Be it known that I, BARTON S. SNOW, a citizen of the United States, residing at Batavia, in the county of Kane and State of Illinois, have invented a new and useful Improvement in Cranes, of which the following is a specification.

My invention relates, more particularly, to improvements in cranes or stand-pipes 10 for use, more especially, in supplying water to tenders of locomotives, these cranes being located along side of the railway track and of a construction adapting the spout portion of the crane to be swung from a position 15 in which it substantially parallels the track and is thus out of the way of trains passing along the track, into a position in which it extends crosswise of the track above the tender to be filled, and vice versa. 20 It is desirable in stand-pipes of the character above stated, to provide for the centering of the spout section in a position generally parallel with the track, and preferably to lock the spout in such position, without 25 requiring the operator to move the spout to its final position, and in this connection, it is one of my objects to provide improved means for accomplishing this purpose whereby the height to which the water in passing 30 through the crane must ascend, when the spout is in discharging position, will be lower than the height to which it is required to be forced in structures as hitherto provided. A further object is to provide a construction 35 wherein accidental return of the spout section to the position in which it extends substantially parallel with the track, after having been swung by the trainman to a position generally crosswise of the track, 40 will be prevented and still permit the desired swinging of the spout section to effect registration of its outlet with the water-filling opening of the tender. Another object is to provide a construction for the purpose stated 45 wherein the spout section shall be so supported that the forces exerted against it, tending to cant it, will be so resisted as to permit the spout section to be swung with ease. Another object is to provide a construction 50 of track and roller cooperating therewith for controlling the up and down movement of the spout, that even in the case of incorporation thereof in prior structures, the height to which the water must be forced

for discharge through the spout will be reduced.

Another phase of my invention relates to water cranes of the type employing a hollow spout-equipped column vertically movable relative to a conduit section in communication therewith and through which the water is supplied to the column. It will be manifest that the tendency of the water rising in the column and thence deflected laterally through the spout section, is to force the column upwardly and consequently raise the discharge end of the spout relative to the filler opening of the tender, it being the practice to so provide water-crane structures that they normally occupy an elevated position and are forced down by the operator to tender-filling position and held, by the operator, in this position. It is another one of my objects to provide against the vertical displacement of the column under the force of water rising therethrough, and thereby avoid danger of the discharge end of the spout becoming displaced relative to the filler opening and avoid the spilling of water such as would occur if the spout lifted out of the filler opening.

Another object is to generally so improve upon water cranes as hitherto provided that they will function to better advantage and be better suited for performing the service for which they are provided.

Referring to the accompanying drawings, Figure 1 is a view in side elevation of a crane constructed in accordance with my invention, the vertical column with its spout section being shown by full lines in the position normally assumed thereby, and by dotted lines in lowered position. Fig. 2 is a view in elevation of the lower end of the crane, certain parts thereof being shown in section. Fig. 3 is a similar view of the same portion of the structure, but viewed at an angle of 90° thereto, the structure being viewed from the right in Fig. 2. Fig. 4 is an enlarged section taken at the line 4—4 on Fig. 2 and viewed in the direction of the arrow. Fig. 5 is an enlarged section taken at the line 5—5 on Fig. 2 and viewed in an upward direction, this view showing the concentric tracks, forming a part of the structure, in full plan. Fig. 6 is a plan section taken at the line 6—6 on Fig. 2 and viewed in a downward direction; and Fig. 7, an en-

larged view in vertical sectional elevation of the concentric tracks, showing the cooperating rollers by dotted lines.

The particular apparatus shown, comprises a hollow base-portion 8 in the form of a casing illustrated as rigidly secured to the top surface of a housing 9 which in practice is located in the ground. The housing contains the pipe 10 which would lead from any suitable source of water supply, this pipe, which is shown as equipped with a gate-valve 11, opening into a valve casing 12 of any suitable construction and which may be in accordance with common practice. The casing 12, in accordance with common practice, contains a valve (not shown) which may be of any suitable construction and which operates vertically to control the passage of water from the pipe 10 out through the outlet of the casing 12, this valve being operated through the medium of the vertically movable mechanism, represented at 13, and from which rises the rods 14 which slide up and down through the upper end of the casing 12, in stuffing boxes 15. The valve-operating mechanism also involves the vertically-extending slide-rods 14^a with a connection between the rods 14 and 14^a of such construction that the rods 14^a may swing around the column 19 with the latter as hereinafter described without swinging the rods 14 but which will be operative to vertically actuate the rods 14 from the rods 14^a, the connection shown involving a ring 14^b loosely surrounding the conduit 18 and having an annular groove 14^c on its inner periphery and a ring 14^d connected with the lower ends of the rods 14^a and extending into the groove 14^c throughout its periphery. The outlet of the casing 12, represented at 16, communicates with an upwardly-extending pipe 17, which extends upwardly through an opening 18 in the top of the housing 9 and into a position wherein it is surrounded by the base-member 8.

The apparatus also comprises a vertically movable and rotatable hollow column 19 provided at its lower end with a collar 20, this column having telescoping relation with the upper end of the pipe 17 whereby the column 19 is adapted to be moved up and down on the pipe 17 for the purpose hereinafter explained. The upper end of the column 19 is provided with a spout portion 21 extending laterally therefrom and terminating in a downwardly-extending outlet portion 22, through which the water, delivered to the crane, as hereinafter described, discharges into the tender, or other receptacle, to be filled.

Surrounding the upper, cylindrical, end of the casing 8 is a cylindrical, sectional, member 23, the internal diameter of the lower end of which is greater than its upper end to provide an annular downwardly-fac-

ing shoulder portion 24 to which a track-equipped ring 25, the tracks of which are provided on the under face of this ring, is secured, the member 23 being supported at the ring 25 on two sets of diametrically-disposed rollers 26 and 27 which are journaled, to rotate, in an annular flange portion 28 formed on the exterior surface of the casing 8, the two sets of rollers being disposed at an angle of 90° to each other. The tracks referred to are represented at 29 and 30, these tracks being concentrically disposed, with the track 29 located within the track 30 as shown, and the sets of rollers 26 and 27, which cooperate respectively with the tracks 29 and 30, are so disposed that they will extend directly beneath these respective tracks, the rollers 26, to this end, being spaced apart a greater distance than the rollers 27.

The apparatus shown also comprises counterbalancing mechanism for the column and spout, this mechanism comprising an upwardly extending tube 31 located at the rear of the column 19 and secured at its lower end in a tubular member 32 connected with, and carried by, the hollow member 23. The upper end of the tube 31 is equipped with a head 33 shown as of frame-like construction which extends upwardly beyond the spout section 21 in the extreme upper position of the latter and is equipped with sheaves 34 and 35 over which a flexible element, represented at 36, and which may be a chain as shown, extends, one end of this element being connected with the spout 21, as represented at 37, and its other end passing downwardly through the tube 31 and connected with the upper end of a counterweight 38 which is slidable up and down in the tube 31, the counter-weight 38 being of such weight that it preferably over-balances the parts which are suspended from the end of the element 36 opposite that to which the counter-weight is attached, whereby the normal position of these parts is that represented in full lines in Fig. 1, to which position these parts automatically return after the column and spout section have been depressed, as for example, to the dotted position shown in Fig. 1. In order that the column 19 with its spout section 21 may be guided at its upper end in its movement vertically, the column 19 is provided with rearwardly extending plate members 39 located at opposite sides of the tube 31, between which plates a peripherally-grooved roller 40 mounted on a shaft 41 carried by these plates, extends, this roller bearing at its grooved-periphery against the tube 31.

In the particular construction illustrated the tracks 29 and 30 are of such form as to provide depressions into which the rollers 27 and 26, respectively, extend when the spout section is swung to a position in which

it substantially parallels the track, these depressions being sufficiently deep to prevent the spout section from being accidentally swung out of the position stated, the portions of these tracks at opposite sides of the depressions referred to sloping downwardly in opposite directions. These tracks are also provided with low portions arranged at angles of 90° to the depressions referred to 10 into which the rollers respectively extend when the spout section extends crosswise of the track, the under surfaces of the tracks at opposite sides of these low portions inclining downwardly in opposite directions, 15 whereby when the spout is swung from a position in which it substantially parallels the track to a position in which it extends crosswise of the track, the member 23, together with the parts carried thereby and 20 including the tube 31, the column 19 and spout section 21, are caused to first rise and then lower, the operator in the initial rotation of the spout forcing the spout toward a position extending crosswise of the track to 25 a position in which the member 23 and the parts carried thereby begin to move downwardly, the remainder of the movement of the spout to crosswise position being effected by the action of gravity. In the reverse 30 rotary movement of the spout section it first rises, under the force exerted by the operator in rotating it, and after it reaches the high places on the cam tracks it automatically continues its rotation to a position in which 35 it extends parallel with the track and becomes locked in the manner heretofore described. To this end the surfaces of the cam tracks are of the shape as shown, the cam track 29 being formed with the diamet- 40 rically-opposed low portions 42 which contain the depressions 43 hereinbefore referred to and into which the rollers 27 extend when the spout section extends substantially parallel with the track, as represented of the 45 roller 27 in Fig. 7. The high portions of the track 29 are represented at 44, there being four of these high portions arranged at 90° to each other, and the low portions of the track 29 which are engaged by the rollers 27 when the spout extends crosswise of the 50 track, are represented at 45, these low portions 45 being diametrically opposed and arranged at 90° to the low portions 42.

The track 30 is formed with the diametri- 55 cally-opposed low portions 46 containing the depressions 47 into which the rollers 26 extend when the spout section extends substantially parallel with the track. The track 30 is also formed with the diametrically-op- 60 posed low portions 48 which are arranged at angles of 90° to the low portions 46 and which oppose the rollers 26 when the spout section extends crosswise of the track, the high portions of the track 30, located between ad- 65 jacent ones of the lower portions 46 and 48,

being represented at 49, there being four of these high portions which extend in the same radial lines as the high portions 44 of the track 29, it being understood from the foregoing description and from the illustration 70 in the drawings, that the under surfaces of these tracks which extend between the high portions and the low portions thereof, are inclined, they being preferably curved surfaces as represented more particularly in 75 Fig. 7.

From the foregoing description it will be observed that when the spout section extends substantially parallel with the track the rollers 26 and 27 will extend into the depressions 47 and 43 respectively, thereby holding the spout-equipped column from accidental rotation. The restraint, however, afforded by the engagement of the rollers with these depressions, as stated, is not sufficient 80 to prevent the operator from turning the column with its spout section to a position in which the latter extends crosswise of the track. In this last-referred-to operation the inclined portions of the tracks in moving 85 against the rollers first cause the member 23 with the parts carried thereby and including the column 19 with its spout section and the supporting mechanism for the counter-weight mechanism, to rise, and after the high 90 spots on these tracks have passed beyond the respective rollers, the member 23 with the various parts referred to lower, it being preferred that the under surfaces of the tracks adjacent the low spots incline as 95 stated whereby the member 23 with the parts carried thereby automatically rotate to move the spout section toward a position in which it extends crosswise of the track, or at least permit the parts to be so positioned with the 100 exertion of relatively slight force on the part of the operator. The telescoping connection between the column 19 and the conduit 17 adapts the column with its spout section to be vertically adjusted to cause 105 the discharge portion 22 of the spout section to extend at the desired elevation for insuring the discharge of the water from the crane into the opening of the tender or other receptacle to be filled. 110

The bottom surfaces of the low portions 45 and 48 of the tracks are so formed that they will present flat portions disposed substantially horizontally and against which the rollers referred to bear when the spout section extends generally crosswise of the track, the purpose of these flat portions being to permit the member 23, together with the parts carried thereby, to be swung for properly adjusting the spout section in a 115 horizontal plane relative to the tender to be filled, without requiring undue exertion on the part of the operator, the parts referred to maintaining the position to which they are rotated for the adjustment purpose 120 125 130

stated, without requiring the operator to hold these parts in the position to which he adjusts them. In this connection it may be stated that in practice the tenders to be filled are not always stopped with their filler openings in exactly the same position relative to the crane and thus it is necessary that the spout be swung into different positions horizontally to cause its discharge portion 22 to properly register with the filler opening, and the provision of the tracks as stated permits of this adjustment being readily effected, but without danger of the spout section being swung to a position in which it will automatically swing back to a position in which it parallels the track, which is a danger that is presented by structures of this type as hitherto provided wherein no low portion is provided in the track for engagement with a co-operating roller when the spout extends generally crosswise of the track.

Furthermore it will be noted that the feature of having the low portions which engage the rollers when the spout section extends generally crosswise of the track is of advantage, especially should the spout-equipped column be so related to the member equipped with the track that this column is not free to move vertically relative to said member, as the height to which the water must be delivered in the crane is greatly reduced as compared with those structures wherein no such low portions are provided in their tracks. However, where the column has telescoped relationship to the conduit through which the water is delivered to the column, the last recited advantage of the particular low portion referred to, of the tracks, is not presented.

The mechanism for controlling the flow of water through the crane and of which the valve mechanism hereinbefore referred to, together with the rods 14 and 14^a, are parts, also comprises a lever 50 pivotally supported between its ends as represented at 51 on the frame 33, the rear end of this lever being forked at which portions it is pivotally connected with the upper ends of the valve-actuating rods 14^a. The outer end of this lever is preferably provided with a depending pull element, as for example a cable, represented at 53, which extends into a position rendering the operation of this lever readily accessible by a person located on the tender to be filled. In the particular arrangement shown the arrangement of the valve and its operating parts is such that when the lever 50 is swung in clockwise direction it operates to open the valve controlling the flow of water through the crane.

As hereinbefore stated, the normal position vertically occupied by the column and spout section is that shown in full lines in

Fig. 1, and as a desirable means for limiting upward movement of these parts I provide the depending yoke 54 which is carried by the frame 33 and is so positioned as to occupy a straddling position relative to the spout section 21 which latter upwardly bears against this yoke when the column and spout section are in uppermost position.

The apparatus shown also comprises means which operate automatically upon the actuation of the valve referred to for controlling the flow of water through the crane, to clamp the column 19 in the position to which it is adjusted in a vertical plane by the operator in positioning the discharge end 22 of the spout section 21, in the filler opening of the receptacle to be filled from the crane, to the end that the rush of water upwardly through the column 19 and against the spout section 22 will not vertically displace these parts which have been positioned by the operator, as stated, these means comprising a pair of segmental brake bands 55 located within the member 23 and surrounding the lower end of the column 19. These brake bands are pivotally connected at their ends, as indicated at 55^a, with levers 56 pivotally supported, as represented at 57 on the member 23. Each brake band 55 is shown as provided intermediate its ends with a radially outward-projecting portion 58 which is positioned directly above an inwardly-extending lug 59 on the inner surface of the member 23, these lugs serving to support the brake members 55 between their ends. The opposed surfaces of the levers 56 forming the sets thereof at opposite sides of the column 19 are upwardly inclined as represented at 60, these surfaces converging upwardly, the upper extremities of the levers 56 being equipped with rollers 61 journaled therein. The levers 56 cooperate with means carried by the valve-actuating rods 14^a, for rocking the levers 56 of each pair thereof in a direction for drawing the brake bands 55 into clamping engagement with the outer surface of the column 19, these means comprising cam heads 62 rigidly secured to the rods 14^a and shaped to present the upwardly-converging surfaces 63 which oppose the rollers 61, whereby when the rods 14^a are raised the engagement of the surfaces 63 with the rollers 61 will operate to actuate the levers 56 for the purpose stated.

In the use of the crane, assuming that the column 19 is in such position of rotation that the spout section 21 extends parallel with the track, in which position the column is in the elevated position shown in full lines in Fig. 1, the operator either by grasping the spout section 21 or an operating lever, represented at 64, secured to the member 23, rotates the member 23 and all of the parts supported thereon, including the column 19,

spout section 21, counterweight mechanism for the column and spout and that part of the valve-operating mechanism including the ring 14^a and the parts connected therewith, into such position that the spout 21 extends substantially crosswise of the track. In thus rotating the parts as stated, the cam tracks 29 and 30 ride at inclined portions thereof against the rollers 27 and 26, respectively, with the result of causing the member 23 and all of the parts carried thereby to rise, and as soon as the high portions 44 and 49 of these cam tracks have passed across the rollers 27 and 26, respectively, the part 23, together with the parts carried thereby, will lower, the rollers 27 and 26 then opposing the low portions 45 and 48 of the tracks, in which position of the parts the spout section will extend substantially crosswise of the track, but by reason of the provision of the substantially flat surfaces provided at the low portions 45 and 48, as hereinbefore described, the spout may have sufficient movement substantially in a horizontal plane in order that it may be properly positioned directly over the filler opening through which the water is to be discharged into the receptacle to be filled. It will be noted in this connection that while the spout is capable of the movement just stated, the upwardly-inclining end surfaces of the low portions 45 and 48, prevent the operator from accidentally rotating the column 19 to a position in which the high portions 44 and 49 pass across the rollers 27 and 26, respectively, and thus danger of the column automatically rotating to a position in which the spout 21 parallels the track is prevented.

The spout 21 having been swung to a position generally crosswise of the track as stated, the operator forces the column 19 and spout section 21 downwardly, against the action of the counterweight mechanism to cause the discharge portion 22 of the spout to enter the filler opening of the receptacle to be filled, the column 19 sliding downwardly on the conduit 17, by reason of the telescoped arrangement of these parts. Upon positioning the spout as stated, the operator rocks the lever 50 in clockwise direction in Fig. 1, thereupon raising the cam block 62 with the result of drawing the bands 55 into clamping engagement with the column 19 for holding the latter against vertical movement, and also operates the valve in the casing 12, to open the conduit 17 to the pipe 10 and thus to the source of water supply, the water thereby discharging through the crane into the receptacle to be filled. The parts of the structure are preferably so arranged that before the water begins to flow upwardly through the crane and against the portion of the pipe which operates to deflect the water laterally, as for example the elbow portion which connects the spout 21 to the column 19, the cam block 62 will have actuated the brake bands 55 to clamping position, so that there will be no danger of the water flowing through the crane forcing the column 19 out of the position to which the operator depressed it as stated. Upon concluding the filling operation the operator releases his grasp on the pull cord 56, whereupon the valve located in the casing 12, together with the valve-operating parts, will return to normal position (Fig. 1), in which this valve is closed, thereby shutting off the flow of water through the crane. In the return of the valve-operating mechanism to normal position as stated, the cam blocks 62 descend to the position shown in Fig. 2, thereby permitting the brake bands 55 to expand out of clamping position relative to the column 19 and freeing the latter for vertical movement on the conduit 17; whereupon the column 19, together with its spout portion, will automatically rise to the normal position shown in Fig. 1, under the action of the counterweight mechanism, assuming that the operator ceases to apply downward force on the spout. The return of the member 23, together with the parts carried thereby, to a position in which the spout section 21 parallels the track, is effected through the medium of either the spout section 21 or the hand lever 64, as desired, it being understood that in the initial turning of these parts, as stated, in either direction, from a position in which the spout extends crosswise of the track, the inclined surfaces of the low portions 45 and 48 of the tracks 29 and 30 ride against the rollers 27 and 26 respectively in which operation the member 23, together with the parts carried thereby, rises. As soon as the high portions 44 and 49 of these tracks move beyond the rollers 27 and 26, respectively, the inclined surfaces of the low portions 45 and 48 of the tracks engage the said rollers and the member 23, together with the parts carried thereby, lower, the member 23, together with the parts carried thereby, continuing its rotation until the depressions 43 and 47 are moved into registration with the rollers 27 and 26, respectively, in which position the spout section extends substantially parallel with the track and these rotating parts are maintained in the position stated against accidental rotation.

By preference, and as shown, the counterweight 38 and the main portion of the flexible element 36, are covered to protect them against the weather for the purpose of preventing these parts from becoming clogged with ice and snow. This is accomplished by providing the tube 31 hereinbefore described and the cover plate 65 which is secured to the upper end of the frame 33 to

extend over the sheaves 34 and 35, together with that portion of the element 36 which extends between these sheaves, and also closes the upper end of the tube 31.

5 While I have illustrated and described a particular construction, I do not wish to be understood as intending to limit my invention thereto as the same may be variously modified and altered without departing 10 from the spirit thereof.

What I claim as new, and desire to secure by Letters Patent, is:

1. In a crane, the combination of relatively rotatable members one of which is a 15 hollow column through which the fluid discharges, one of said members having cam-tracks one within the other, and the other of said members having series of projecting parts certain of said projecting parts engaging one track and the others thereof engaging the other track, one of said members being supported by said tracks and said parts, the said series of projecting parts being 20 out of radial alignment.

2. In a crane, the combination of relatively rotatable members one of which is a hollow column through which the fluid discharges, one of said members having cam-tracks one within the other, and the other 30 of said members having series of rollers certain of which engage one track and the others thereof engaging the other track, one of said members being supported by said tracks and said rollers, the said series of 35 rollers being out of radial alignment.

3. In a crane, the combination of relatively rotatable members one of which is a hollow column through which the fluid discharges, one of said members having cam-tracks one within the other, and the other 40 of said members having series of projecting parts arranged substantially 90° apart, certain of said projecting parts engaging one track and the others thereof engaging the other track, one of said members being supported by said tracks and said parts.

4. In a crane, the combination of relatively rotatable members one of which is a hollow column through which the fluid discharges, one of said members having cam-tracks one within the other, and the other 50 of said members having series of rollers arranged substantially 90° apart, certain of said rollers engaging one of said tracks and the others thereof engaging the other track.

5. In a crane, the combination of a conduit for fluid, a hollow column rising from, and communicating with, said conduit adapted to be rotated and moved up and 60 down relative to said conduit, said column having a laterally-extending spout portion, a cam-track and cooperating projecting parts at which said column is supported, said track and projecting parts being relatively 65 movable about the axis of said column 66

and up and down, said track containing low portions with which said projecting parts engage when said spout portion extends crosswise of the track adjacent to which the crane extends and other low portions with 70 which said projecting parts engage when said spout extends substantially parallel with the track.

6. In a crane, the combination of a conduit for fluid, a hollow column rising from 75 and communicating with said conduit and adapted to be rotated and moved up and down relative to said conduit, said column having a laterally-extending spout portion, a cam-track, and cooperating rollers at 80 which said column is supported, said track and rollers being relatively movable about the axis of said column and up and down, said track containing low portions with which said rollers engage when said spout extends crosswise of the track adjacent to which the crane extends and other low portions with 85 which said rollers engage when said spout extends substantially parallel with the track. 90

7. In a crane, the combination of a conduit for fluid, a hollow column rising from 95 and communicating with said conduit adapted to be rotated and moved up and down relative to said conduit, said column having a laterally-extending spout portion, a cam-track, co-operating projecting parts at which said column is supported, said track and projecting parts being relatively 100 movable about the axis of said column and up and down, said track containing low portions with which said projecting parts engage when said spout portion extends crosswise of the track adjacent to which the crane extends and other low portions with 105 which said projecting parts engage when said spout extends substantially parallel with the track, and means whereby said column and spout section are held against accidental rotation 110 out of the position in which the spout extends substantially parallel with the track. 115

8. In a crane, the combination of relatively rotatable members one of which is a hollow column through which the fluid discharges, one of said members having a cam-track and the other having a projecting part 120 engaging said track, one of said members being supported by said track and said part, said column having a laterally-extending spout portion and said cam-track containing a low portion the bottom surface of which is substantially flat and with which said projecting part engages when said column is turned to a position in which its spout portion extends substantially crosswise of the track alongside of which the crane is located. 125

9. In a crane, the combination of a conduit, a hollow rotatable column having telescoped relation with said conduit and hav- 130

- ing a laterally-extending outlet portion, means operating to effect automatic rotation of said column to a normal position of rotation, said column and said outlet portion 5 being movable up and down relative to said means, and counterbalancing mechanism for said column.
10. In a crane, the combination of a conduit, a hollow rotatable column having telescoped relation with said conduit and having a laterally-extending outlet portion, means operating to effect automatic rotation of said column to a normal position of rotation, said column being movable up and 15 down relative to said means, and means releasably maintaining said column in said normal position.
11. In a crane, the combination of a conduit, a hollow rotatable column having telescoped relation with said conduit and having a laterally-extending outlet portion, and roller and cam-track elements, one of said 20 elements being bodily rotatable with said column and the other of said elements being stationary relative to said bodily rotatable element, said column being movable up and 25 down relative to said elements.
12. In a crane, the combination of a conduit, a hollow rotatable column having telescoped relation with said conduit and having a laterally-extending outlet portion, a cam-track rotatable with said column, and rollers in engagement with which said track rotates, said column being movable up and 30 down relative to said cam-track and rollers. 35
13. In a crane, the combination of relatively rotatable members one of which is a hollow column through which the fluid discharges, one of said members having a cam-track and the other having a projecting part engaging said track, one of said members being supported by said track and said part, said column having a laterally-extending spout portion and said cam-track containing a low portion engaged by said 40 part when said column is turned to a position in which its spout section extends substantially parallel with the track alongside of which the crane is located, and with a substantially flat surface engaged by said 45 part when said spout is swung into a position in which it extends substantially cross-wise of the track.

BARTON S. SNOW.
